WINDING MACHINE

Raymond V. Tata, Providence, R. I., assignor to
 Universal Winding Co., Cranston, R. I., a corporation of Massachusetts

Application May 3, 1950, Serial No. 159,691

9 Claims. (Cl. 242—18)

1

The present invention relates to improvements in winding machines and particularly to a mechanism for winding a reserve length of yarn on the end of a core or other package-support before winding the package itself.

In the following specification and claims the term "yarn" is employed in a general sense to apply to all kinds of strand materials, either textile or otherwise, and the designation "package" is intended to mean the product of the winding machine whatever its form.

The present invention provides a device for attachment to or incorporation in a winding machine to adapt said machine to wind a "transfer tail" or "tail-end" on the end of a package core before the winding of the actual package commences. The "transfer tails" or "tail-ends" thus wound are employed to magazine a plurality of packages on a creel or other yarn holder by tying the transfer tail of one package to the leading end of a second package so that the yarn will deliver continuously from the several packages.

One object of the present invention is to provide a mechanism for winding a "transfer tail" or "tail-end" on the end of a package core.

Another object of the present invention is to provide a mechanism that has relatively few moving parts for winding a "transfer tail" or "tail-end" on the end of a package core.

Another object of the present invention is to provide a mechanism for winding a "transfer tail" or "tail-end" on the end of a package core that does not need to be reset after a "transfer tail" or "tail-end" has been wound before another can be wound.

Other objects of the invention will in part be obvious and will in part appear hereinafter.

The invention accordingly comprises the apparatus possessing the construction, combination of elements and arrangement of parts which are exemplified in the following detailed disclosure, and the scope of the application of which will be indicated in the claims.

For a fuller understanding of the nature and objects of the invention, reference should be had to the following detailed description taken in connection with the accompanying drawings wherein:

Figure 1 is a diagrammatic fragmentary view of a winding machine incorporating the transfer tail winding mechanism of the present invention;

Fig. 2 is a side elevation of the rotating yarn guide; and

Fig. 3 is an end view of the rotating yarn guide.

The present invention comprises a rotating

2

yarn guide in the form of a toothed wheel adapted to rotate about an axis generally parallel to the axis of the package core upon which the transfer tail and the package of yarn is to be wound.

5 The rotating yarn guide is positioned so that its end surface is opposite the location on the package core that is to receive the transfer tail, and outside of the traverse of a reciprocating yarn guide employed in the formation of the yarn package. When the winding of a package of yarn is commenced the end of the yarn to be wound is drawn diagonally from the supply of yarn to be wound across the end of the rotating yarn guide and attached to the end of the package core. The 10 rotating yarn guide holds the strand of yarn a predetermined length of time and permits the package core, upon rotation thereof, to wind the desired transfer tail. Upon continued rotation of the rotating yarn guide the strand of yarn is passed between two of its teeth and permitted to move out of engagement with said rotating yarn guide and into the path of the reciprocating yarn guide which picks it up and proceeds to wind the desired package.

15 Referring now to Fig. 1 of the drawing wherein there is shown a fragmentary diagrammatic view of one unit of the winding portion of a more or less conventional uptwister and including a twisting spindle. A driving roll 10 is rotatably carried by shaft 12 suitably journaled in a pair of end frames 14 (only one of which is shown) of the uptwister. Shaft 12 and roll 10 are rotated by any suitable means. A package core 16 adapted to have a transfer tail wound on a relatively short portion of its length adjacent one of its ends and a package of yarn wound thereon adjacent said transfer tail, is mounted on arbor 18 and is adapted to be rotated by surface contact with driving roll 10. Arbor 18 and package 20 core 16 are carried for pivotal movement towards and away from driving roll 10 to allow for growth of the package of yarn and to permit doffing and donning operations by arm 20, which is pivotally attached to a mounting bracket (not shown) 25 forming a part of the uptwister. A traverse bar 22 is reciprocated parallel to the axis of package core 16, through a stroke of predetermined length equal to the length of the package that it is desired to wind, by suitable cam means (not shown),

30 and carries a self-threading yarn guide 24 adjacent package core 16 by means of yarn guide arm 26. A spindle 28 is suitably mounted on the uptwister frame for rotation by endless belt 30.

35 A bobbin 32 containing a supply of yarn Y for the package being wound on package core 16 is ro-

40 garded by a suitable cam means (not shown) and carries a self-threading yarn guide 24 adjacent package core 16 by means of yarn guide arm 26. A spindle 28 is suitably mounted on the uptwister frame for rotation by endless belt 30.

45 A bobbin 32 containing a supply of yarn Y for the package being wound on package core 16 is ro-

50 garded by a suitable cam means (not shown) and carries a self-threading yarn guide 24 adjacent package core 16 by means of yarn guide arm 26. A spindle 28 is suitably mounted on the uptwister frame for rotation by endless belt 30.

55 A bobbin 32 containing a supply of yarn Y for the package being wound on package core 16 is ro-

tatably carried by spindle 28 which imparts a predetermined number of turns of twist per unit length to said yarn Y as it is drawn off bobbin 32. Spindle 28 is located below and in front of the midpoint of package core 16 that is to receive the package of yarn, and a fixed yarn guide 34 is fixedly mounted directly above spindle 28 on a longitudinal frame member (not shown). All of the structure thus far described is broadly conventional and well known to those skilled in the art.

A rotating yarn guide 36, preferably moulded of plastic, is mounted on shaft 38 for rotation thereby opposite one end of package core 16 and beyond the length thereof traversed by guide 24. Rotating yarn guide 36 is provided with a hub portion 40 having an axial bore 42 extending therethrough and a longitudinal locking rib 44 on the wall of said bore. The diameter of bore 42 is slightly larger than the diameter of shaft 38 and locking rib 44 has a height greater than the difference in said diameters and frictionally holds guide 36 at any desired location on shaft 38. A plurality of generally triangular shaped yarn guide teeth 46 extend in a generally radial direction from one end of hub 40 to form a flange provided with a plurality of slots 48 having their center lines generally tangent to the wall of bore 42. Guide 36 is adapted to be rotated by shaft 38 in a direction generally counterclockwise as viewed in Fig. 3 for a reason that will become apparent hereinafter.

Shaft 38 and yarn guide 36 preferably rotate at a slower speed than package core 16 to permit said core 16 to wind a transfer tail of sufficient length to be useful in magazining the wound packages in the above described manner. However, the exact ratio of the speed of package core 16 to the speed of yarn guide 36 is a matter of choice and is determined by the length of transfer tail that is desired. In the embodiment disclosed in the drawing shaft 38 is journaled in end frames 14 so as to be substantially parallel to shaft 12 and above a straight line drawn between stationary yarn guide 34 and the point of contact between driving roll 10 and package core 16 so that a strand of yarn passing through guide 34 and being wound on core 16 lays across said shaft 38 at an appreciable angle. Shaft 38 is rotated in a clockwise direction as viewed in Fig. 1 by shaft 12 through bevel gears 50 and 52 carried respectively by shaft 12 and one end of shaft 54, and worm 56, and worm wheel 58 carried respectively by the other end of shaft 54 and the end of shaft 38. It will, however, be obvious to those skilled in the art that shaft 38 and yarn guide 36 can be rotated by any other convenient means.

The mechanism of the present invention operates in the following manner to automatically wind a transfer tail on the end of package core 16 and following the winding of said transfer tail release the yarn for engagement by self-threading yarn guide 24. An empty package core 16 is placed on arbor 18 and is moved out of engagement with driving roll 10. The end of yarn Y is drawn from bobbin 32 upwardly through stationary yarn guide 34 and attached to the end of package core 16 that is to carry the transfer tail, i. e. the end adjacent rotating yarn guide 36. Spindle 28 is then moved into engagement with endless belt 30 to cause it and bobbin 32 to rotate and impart twist to the length of yarn extending between bobbin 32 and package core 16. Package core 16 is then pivoted downwardly into engagement with driving roll 10 which will rotate

it in a counterclockwise direction as viewed in Fig. 1 and simultaneously the length of yarn Y extending from stationary yarn guide 34 to package core 16 is drawn to the left, as viewed in Fig. 1, and laid over shaft 38 to the left of rotating yarn guide 36 to form the two lengths Y¹ and Y² extending between guide 34 and rotating guide 36 and rotating guide 36 and package core 16 respectively. Yarn guide 36 serves as a stop and prevents yarn Y from sliding to the right along shaft 38 into the path of reciprocating yarn guide 24 until a transfer tail of the desired length has been wound. As rotating yarn guide 36 turns, one of the slots 48 formed therein will coincide with the length of yarn Y¹ extending between the two yarn guides 34 and 36, and when this condition occurs, said length of yarn will be drawn through said slot due to the fact that both slot 48 and yarn Y¹ are tangent to shaft 38 and length of yarn Y¹ is under tension to the right. Continued rotation of rotating yarn guide 36 permits yarn Y to leave slot 48 when the slot 48 carrying yarn Y has been rotated until it substantially coincides with length of yarn Y². When this occurs, the lengths Y¹ and Y² slide to the right along shaft 38 and length Y² also moves towards the midpoint of package core 16 and into the path of reciprocating yarn guide 24 which picks it up and traverses it back and forth across a predetermined length of core 16 to wind a self-supporting package.

Whereas the present invention has been disclosed and described in connection with the winding mechanism associated with a yarn twisting mechanism, it will be understood that the transfer tail winding mechanism of the present invention can be applied to other types of winding machines.

Since certain changes may be made in the above apparatus without departing from the scope of the invention herein involved, it is intended that all matter contained in the above description or shown in the accompanying drawing shall be interpreted as illustrative and not in a limiting sense.

What is claimed is:

1. In a winding machine the combination comprising means for rotatably holding a package core adapted to have a transfer tail wound on one portion of its length and a yarn package wound on another portion of its length, means for rotating said core, means for traversing a strand of yarn across the package receiving portion of said core to wind a package of yarn thereon, a rotating yarn guide comprising a hub carrying a flange, said flange having a slot extending therethrough, means rotatably holding said guide opposite the transfer tail receiving portion of said core for rotation around an axis substantially parallel to the axis of said core whereby said yarn guide holds said strand of yarn in line with said transfer tail receiving portion for a predetermined length of time to permit rotation of said core to wind a transfer tail thereon.

2. In a winding machine the combination comprising means for rotatably holding a package core adapted to have a transfer tail wound on one portion of its length and a yarn package wound on another portion of its length, means for rotating said core, means for traversing a strand of yarn across the package receiving portion of said core to wind a package of yarn thereon, a rotatable shaft generally parallel to the axis of said package core, and a rotating yarn

guide carried by said shaft opposite the transfer tail receiving portion of said core, said rotating yarn guide comprising a hub and a flange, said flange having a slot substantially tangent to said shaft formed therein, said flange being adapted to hold said strand of yarn in line with said transfer tail receiving portion for a predetermined length of time to permit rotation of said core to wind a transfer tail thereon, and said slot being adapted to release said strand from said flange at the end of said predetermined length of time.

3. In a winding machine the combination comprising means for rotatably holding a package core adapted to have a transfer tail wound on one portion of its length and a yarn package wound on another portion of its length, means for rotating said core, means for traversing a strand of yarn across the package receiving portion of said core to wind a package of yarn thereon, a rotating yarn guide comprising a flange, said flange having a slot extending therethrough, means rotatably holding said guide opposite the transfer tail receiving portion of said core for rotation around an axis substantially parallel to the axis of said core whereby said yarn guide holds said strand of yarn in line with said transfer tail receiving portion for a predetermined length of time to permit rotation of said core to wind a transfer tail thereon.

4. In a winding machine the combination comprising means for rotatably holding a package core adapted to have a transfer tail wound on one portion of its length and a yarn package wound on another portion of its length, means for rotating said core, means for traversing a strand of yarn across the package receiving portion of said core to wind a package of yarn thereon, a rotatable shaft generally parallel to the axis of said package core, and a rotating yarn guide carried by said shaft opposite the transfer tail receiving portion of said core, said rotating yarn guide comprising a flange, said flange having a slot substantially tangent to said shaft formed therein, said flange being adapted to hold said strand of yarn in line with said transfer tail receiving portion for a predetermined length of time to permit rotation of said core to wind a transfer tail thereon, and said slot being adapted to release said strand from said flange at the end of said predetermined length of time.

5. In a winding machine the combination comprising means for rotatably holding a package core adapted to have a transfer tail wound on one portion of its length and a yarn package wound on another portion of its length, means for rotating said core, means for traversing a strand of yarn across the package receiving portion of said core to wind a package of yarn thereon, and a rotating yarn guide located opposite the transfer tail receiving portion of said core, said rotating guide comprising a hub member having projections on its periphery adapted to hold said strand of yarn in line with said transfer tail receiving portion for a predetermined length of time to permit rotation of said core to wind a transfer tail thereon.

6. In a winding machine the combination comprising means for rotatably holding a package core adapted to have a transfer tail wound on one portion of its length and a yarn package wound on another portion of its length, means for

rotating said core, means for traversing a strand of yarn across the package receiving portion of said core to wind a package of yarn thereon, and a rotating yarn guide located opposite the transfer tail receiving portion of said core, said rotating guide comprising a cylindrical element having projections on its periphery adapted to hold said strand of yarn in line with said transfer tail receiving portion for a predetermined length of time to permit rotation of said core to wind a transfer tail thereon.

7. In a winding machine the combination comprising means for rotatably holding a package core adapted to have a transfer tail wound on one portion of its length and a yarn package wound on another portion of its length, means for rotating said core, means for traversing a strand of yarn across the package receiving portion of said core to wind a package of yarn thereon, and a continuously rotating yarn guide located opposite the transfer tail receiving portion of said core adapted to hold said strand of yarn in line with said transfer tail receiving portion for a predetermined length of time to permit rotation of said core to wind a transfer tail thereon.

8. In a winding machine the combination comprising means for rotatably holding a package core adapted to have a transfer tail wound on one portion of its length and a yarn package wound on another portion of its length, means for rotating said core, means for traversing a strand of yarn across the package receiving portion of said core to wind a package of yarn thereon, a continuously rotating yarn guide, means rotatably holding said guide opposite the transfer tail receiving portion of said core for rotation around an axis substantially parallel to the axis of said core whereby said yarn guide holds said strand of yarn in line with said transfer tail receiving portion for a predetermined length of time to permit rotation of said core to wind a transfer tail thereon.

9. In a winding machine the combination comprising means for rotatably holding a package core adapted to have a transfer tail wound on one portion of its length and a yarn package wound on another portion of its length, means for rotating said core, means for traversing a strand of yarn across the package receiving portion of said core to wind a package of yarn thereon, a continuously rotating yarn guide having a slot in its periphery, means rotatably holding said guide opposite the transfer tail receiving portion of said core for rotation around an axis substantially parallel to the axis of said core whereby said yarn guide holds said strand of yarn in line with said transfer tail receiving portion for a predetermined length of time to permit rotation of said core to wind a transfer tail thereon.
